Primary Examiner — Sheryl Lane*Assistant Examiner* — Calvin E Vasant(74) *Attorney, Agent, or Firm* — KA Filing LLC; Wayne V. Harper(57) **CLAIM**

I claim the ornamental design for a shower head, as shown and described.

DESCRIPTION

FIG. 1 is a perspective view of a shower head showing my new design;

FIG. 2 is other perspective view thereof;

FIG. 3 is a front view thereof;

FIG. 4 is a back view thereof;

FIG. 5 is a right-side view thereof;

FIG. 6 is a left-side view thereof; and,

FIG. 7 is a top view thereof.

The broken lines are only for environmental purposes and form no part of the claimed design.

1 Claim, 7 Drawing Sheets(56)
